WALL AND CEILING FINISH

Leslie S. Odell, Montreal, Quebec, Canada, assignor to Building Products Limited, Montreal, Quebec, Canada

Application January 28, 1941, Serial No. 376,360
In Canada April 3, 1940

1 Claim. (Cl. 20—4)

This invention relates to wall and ceiling finishes; and it comprises a method of covering inside walls and ceilings with wall board panels to give the appearance of a wall paper finish.

According to this invention insulating wall board panels, preferably of the laminated or multi-ply paper board type, are first nailed to the studding and headers of the wall or ceiling structure to be covered, said panels being arranged in courses so that the joints between the meeting edges of the panels contained in the same course are staggered in relation to the joints formed by the meeting edges of the panels contained in the adjoining course or courses. The laminated panels should be of substantial thickness and stiffness and may consist of any desired number of plies of paper board or other fibrous material cemented together in the usual manner. These panels are preferably of rectangular shape and may be of any suitable length and width. In the preferred embodiment the width of the panels applied to cover a vertical wall of a room or the like is preferably such that three horizontally applied courses of the panels will completely cover the wall surface from the floor line to the ceiling. After the laminated panels have been applied to a vertical wall structure in horizontal courses, they are covered by vertically extending single-ply panels, made of the same material. The single-ply panels are butted together in edge to edge relation and are of sufficient length to extend from the floor line to the ceiling. The single-ply panels are relatively thin so that the vertical joints formed by and between their meeting edges are substantially as inconspicuous as the butt joints formed in applying wall paper. The single-ply panels are normally flat and rigid so that it is a simple operation to apply these panels so that their vertical edges may be butted together to form a very thin line or joint. It is also desirable that the single-ply panels be applied so that the vertical joints formed between their meeting edges are staggered in relation to the vertical joints formed between the meeting edges of the laminated panels. The single-ply panels are secured in place by pasting them to the outer surface of the laminated panels, the single-ply panels being then sized and painted to provide a finish which is comparable with that of a wall paper finish and which eliminates the necessity of using battens or other unsightly expedients for covering the joints formed by and between the meeting edges of the laminated panels.

The procedure followed in applying the same

finish to a ceiling is substantially the same as that described in connection with the finishing of a vertical wall structure. The laminated panels are nailed to the ceiling structure in courses, with the panels of the one course staggered in relation to the panels of the adjacent course or courses. The single-ply finishing panels are then pasted to the multi-ply panels and are preferably of such a length as to extend across the ceiling from wall to wall. In covering both wall and ceiling structures, it is preferred that the single-ply panels be made of the same material and preferably of the same thickness as one of the component plies of the laminated panels so that both the laminated and single-ply panels will have substantially the same coefficient of expansion. It is also preferred that the laminated panels and the covering single-ply panel be secured in place so that the grain of the single-ply panels is at right angles to the grain of the laminated panels which they cover.

The present invention makes it feasible to use large headed nails for nailing both the marginal and the intermediate portions of the laminated panels to the studding and headers of the wall or ceiling structures since these nails are completely covered by the subsequently applied single-ply panels.

Proceeding now to a more detailed description reference will be had to the accompanying drawings, wherein—

Fig. 1 is a perspective view showing the studding and headers of a portion of a wall such, for example, as the vertical wall of a room or similar enclosure.

Fig. 2 is a view showing the manner in which the laminated wall board panels are nailed to the wall structure appearing in Fig. 1.

Fig. 3 is a view showing the manner in which the laminated wall board panels appearing in Fig. 2 are covered by single-ply panels of the same material to give a wall paper finish.

Fig. 4 is a perspective view showing one form of laminated panel which may be used in accordance with this invention.

Fig. 5 is a perspective view showing one of the single-ply panels.

Fig. 6 is an iso-metric view illustrating the application of the invention to both the walls and ceiling of a room.

Referring to the drawings, 5 designates a wall structure such as the wall of a room or similar enclosure, said structure comprising studding 6 and headers 7. According to this invention the inside of the wall structure 5 is first covered by

laminated wall board panels 8 arranged horizontally in superposed courses. The marginal portions of each panel 8 are fastened to the studding 6 and headers 7 by large headed nails as indicated at 9. The intermediate portions of the panels 8 are also nailed to intermediate studding elements 7 as indicated at 10. This method of nailing the panels to the studding and header elements of the wall structure provides a very stiff insulating wall structure and is permissible by reason of the fact that the fastening nails are concealed from view by the single-ply finishing panels which are subsequently applied as hereinafter described. It will be noted that the panels 8 are of such width that the three courses applied to the wall structure 5 are sufficient to cover the inside of said wall structure from the floor line 11 to the ceiling line 12. As shown more clearly in Fig. 4 each panel comprises a laminated unit consisting of three layers 8a of paper or pulp board cemented together by interposed layers 8b of asphalt. This construction is cited merely by way of example as the panels may consist of any number of plies, the principal consideration being that each panel be of substantial thickness and stiffness.

After the laminated panels 8 have been applied as shown in Fig. 2 the exposed surfaces thereof are covered by narrow single-ply panels 14 which extend from the floor to the ceiling and cover both the horizontal and vertical joints between adjacent laminated panels 8. The single-ply panels 14 are normally flat and thin as shown in Fig. 5 and are comparatively rigid. These single-ply panels are preferably made of the same material as the component plies 8a of the laminated panels 8 and therefore have the same coefficient of expansion. The grain of the single-ply panels 14, when applied as shown in Fig. 3, extends in the longitudinal direction of said panels and is at right angles to the grain of the laminated panels 8. The single-ply panels are relatively thin so that the vertical joints 15 formed between their vertical meeting edges are no more noticeable than the vertical joints between similar strips of ordinary wall paper.

It is also important that the vertical joints 15 formed between the single-ply panels 14 be staggered in relation to the vertical joints 17 formed between the vertical meeting edges of the laminated panels 8. After the single-ply panels have been applied, as shown in Fig. 3, they are sized and painted to give a finish in which the joints between the vertical meeting edges of said panels are substantially inconspicuous.

In Fig. 6 I have shown a portion of a room having the wall board panels 8 and 14 applied to the vertical wall structure of the room as previously described in connection with Figs. 1 to 3 inclusive.

Fig. 6 also shows the method of applying the panelling to the ceiling. In this connection, it will be noted that the laminated panels 8 are nailed to the studding and headers of the ceiling structure in rows or courses. Wherever practicable, the single-ply finishing panels 14 of the ceiling are made of sufficient length to extend entirely across the ceiling from wall to wall. In some cases, of course, the finishing panels must be made shorter to take care of skylights or other openings.

While the laminated panels may be of any desired dimension, I have found it convenient to use panels 3 ft. in width by 10 ft. in length. 20 The single-ply finishing panel should be of a length equal to the prevailing height or width of the wall to which these panels are applied. In practice I have found it convenient to use single-ply panels varying in width from 18 to 24 ins.

Having thus described what I consider to be the preferred embodiments of this invention, it will be understood that various minor changes in the construction may be resorted to within the scope and spirit of the invention as defined by the appended claim.

Having thus described my invention, what I claim is:

An inside finish for a wall or ceiling structure, comprising relatively thick and stiff fibrous panels arranged in courses completely covering the inner side of said structure and a plurality of narrower finishing panels arranged in courses extending at right angles to said first mentioned courses, each of said first mentioned panels comprising a number of layers of paper board cemented together to form a laminated panel structure and each of said finishing panels comprising a single layer of paper board made of the same material and of the same thickness as one of the component layers of said first mentioned panels, said finishing panels being butted together in edge to edge relation and being pasted to the outer surfaces of the first mentioned panels so that the vertical joints formed by and between the vertical edges of the finishing panels are staggered with respect to some of the vertical joints formed by and between the vertical meeting edges of the underlying laminated panels.
